CLAIM

The ornamental design for a handle assembly, as shown and described.

DESCRIPTION

FIG. 1 is a first perspective view of a handle assembly showing my new design;

FIG. 2 is a second perspective view thereof;

FIG. 3 is a third perspective view thereof;

FIG. 4 is a fourth perspective view thereof;

FIG. 5 is a fifth perspective view thereof;

FIG. 6 is a sixth perspective view thereof;

FIG. 7 is a seventh perspective view thereof; and,

FIG. 8 is an eighth perspective view thereof.

The broken lines in the drawings illustrate portions of the handle assembly which form no part of the claimed design.
